UNITED STATES PATENT OFFICE.

VICTOR J. MERCERON, OF PHILADELPHIA, PENNSYLVANIA, ASSIGNOR TO
THE PERFECTION PLAYING CARD COMPANY, OF SAME PLACE.

DESIGN FOR A PLAYING-CARD.

SPECIFICATION forming part of Design No. 16,868, dated August 24, 1886.

Application filed July 15, 1886. Serial No. 208,161. Term of patent 3½ years.

To all whom it may concern:

Be it known that I, VICTOR J. MERCERON, a citizen of the United States, residing at Philadelphia, in the county of Philadelphia and State of Pennsylvania, have invented and produced a new and original Design for Playing-Cards, of which the following is a specification, reference being had to the accompanying drawings, forming part thereof.

10 Heretofore playing-cards have been made with even edges. The conventional shape of such articles is quadrangular, the side and upper and lower edges being each in right lines and at respective right angles, forming a parallelogram.

15

My design consists in a playing-card having its edge or entire perimeter provided with a continuous series of uneven irregular notches, as plainly shown in the drawings, in which A represents one card of a pack of playing cards, 20 and a the notched sides and top and bottom edges thereof.

I claim—

The design for a playing-card herein shown and described, having its edges composed of 25 a continuous series of irregular notches.

VICTOR J. MERCERON.
